US00D853782S

(12) **United States Design Patent** (10) Patent No.: **US D853,782 S**
Conti et al. (45) Date of Patent: ** Jul. 16, 2019

(54) **FOOD PROCESSOR**

- (71) Applicant: **WHIRLPOOL CORPORATION**,
Benton Harbor, MI (US)
- (72) Inventors: **Michael Conti**, St. Joseph, MI (US);
John W. McConnell, St. Joseph, MI
(US); **Mansour Ourasanah**, Chicago,
IL (US)
- (73) Assignee: **Whirlpool Corporation**, Benton
Harbor, MI (US)

Primary Examiner — Barbara Fox*Assistant Examiner* — Mehri F Bajoul(74) *Attorney, Agent, or Firm* — Price Heneveld LLP(57) **CLAIM**

The ornamental design for a food processor, as shown and described.

DESCRIPTION

FIG. 1 is a front perspective view of a food processor according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings depict portions of the food processor that forms no part of the claimed design.

1 Claim, 7 Drawing Sheets# US D853,782 S
